**SOUND REFLECTING DEVICE FOR SPEECH
PRACTICE**

Bernard A. Cousino, 3946 Londonderry Lane,
Toledo, Ohio

Filed Apr. 11, 1960, Ser. No. 60,140

Term of patent 14 years

(Cl. D25—1)

FIG. 1.

FIG. 2.

FIG. 3.

Fig. 1 is a front perspective view of a sound reflecting device for speech practice, showing my new design;

Fig. 2 is a rear perspective view, to a reduced scale; and

Fig. 3 is a side elevational view, to an enlarged scale, the opposite side being substantially a mirror image thereof.

The dominant features of my design reside in the portions shown in full lines.

I claim:

The ornamental design for a sound reflecting device for speech practice, substantially as shown and described.
